CLAIM

The ornamental design for a combined housing for a computer display, a portable processing unit, and an input and output interface module, as shown and described.

DESCRIPTION

FIG. 1 is an exploded top rear and side perspective view of the combined housing for a computer display, a portable processing unit, and an input and output interface module showing our new design;

FIG. 2 is a side view thereof shown in an operative position, the opposite side being identical in appearance; FIG. 3 is a side view thereof with the portable processing unit and the input and output interface module being unattached;

FIG. 4 is an enlarged bottom front and opposite side perspective view of the portable processing unit shown separately for clarity of illustration only;

FIG. 5 is an enlarged top plan view of the input and output interface module shown separately for clarity of illustration only;

FIG. 6 is an exploded front view of the computer display and the portable processing unit shown separately for clarity of illustration only; and,

FIG. 7 is an enlarged bottom front and side view of the input and output interface module shown separately for clarity of illustration only.

UNITED STATES PATENT AND TRADEMARK OFFICE
CERTIFICATE OF CORRECTION

PATENT NO. : Des. 342,236
DATED : December 14, 1993
INVENTOR(S) : Albano et al.

It is certified that error appears in the above-identified patent and that said Letters Patent is hereby corrected as shown below:

On the title page:

In item [57] **DESCRIPTION**, please delete the old descriptions for Figures 2-4 and insert the following descriptions:

-- Figure 2 is an enlarged side view thereof shown in an operative position, the opposite side being identical in appearance.

Figure 3 is an enlarged side view thereof with the Portable Processing Unit and the Input And Output Interface Module being unattached.

Figure 4 is an enlarged bottom rear and side perspective view of the Portable Processing Unit shown separately for clarity of illustration only. --
